FISH HOLDER FOR STRINGERS

George J. Sharps, Momence, Ill., assignor to P & K Incorporated, Momence, Ill., a corporation of Illinois

Application April 5, 1954, Serial No. 29,872

Term of patent 14 years

(Cl. D31—4)

FIG. 1.

Fig. 1 is a view in elevation of a fish holder for stringers showing my new design, and

Fig. 2 is a similar view showing the holder in open position.

I claim:

The ornamental design for a fish holder for stringers, as shown.
